UNITED STATES PATENT OFFICE.

DAWSON M. TAGGART, OF EAST ORANGE, NEW JERSEY, ASSIGNOR TO WESTERN ELECTRIC COMPANY, INCORPORATED, OF NEW YORK, N. Y., A CORPORATION OF NEW YORK.

ARTIFICIAL BUSY-CIRCUITS.

1,400,103.

Specification of Letters Patent. Patented Dec. 13, 1921.

Application filed September 4, 1919. Serial No. 321,534.

To all whom it may concern:

Be it known that I, DAWSON M. TAGGART, a citizen of the United States, residing at East Orange, in the county of Essex, State 5 of New Jersey, have invented certain new and useful Improvements in Artificial Busy-Circuits, of which the following is a full, clear, concise, and exact description.

This invention relates to a circuit arrangement for use in connection with trunks out-going from one telephone exchange to another.

It is the object of this invention to provide means whereby a desired group of trunks 15 may be rendered busy at the office from which they are outgoing under the control of an operator at the office at which they terminate.

In multi-office systems in which the lines 20 of calling subscribers may be extended to manual operators' positions by the use of automatic switches, it will frequently occur that several groups of trunks which are served by the same automatic switches extend to the same manual office, where they 25 may appear at the positions of adjacent operators. During the rush hours of the day, all of these groups of trunks will probably be in use, but during the light load hours, 30 the number of operators at the manual exchange will be materially reduced. It is, therefore, desirable that when the operators leave their positions, they may render the groups of trunks which respectively have 35 access to their positions busy, so that the only group of trunks which may be seized contains trunks leading to a position at which there will be an operator.

Previous schemes for accomplishing this 40 result generally utilize a special pair of conductors extending from the operator's position back to the mechanical office at which point an automatic switch is controlled over this special pair of conductors, to apply busy 45 potential to the sleeves of the trunks leading to such position from the mechanical office. It is obvious that when a large number of mechanical offices have access to one position, that the number of pairs of conductors 50 extending back to the mechanical offices be-

comes an item of considerable importance in view of the high cost of telephone cable.

A feature of the invention is the manner in which a group of trunks may be made artificially busy under the control of an 55 operator at the distant end of such trunks, the control being over the talking conductors of any one of such trunks.

A further feature of the invention resides in the fact that the release of the artificial 60 busy condition may be controlled over the conductors of any trunk in the group of trunks which has been rendered busy.

It is thought that the invention will be best understood from the following detailed 65 description, reference being had to the accompanying drawings.

In the drawings, Figure 1 shows a group of trunks extending from an automatic office to a manual office and shows the apparatus by means of which the busy condition of the trunks may be controlled. The dotted rectangle in the lower right-hand portion of the drawing shows apparatus at a wire chief's or other attendant's position. 70

In practice, the trunks would terminate at the manual office in plugs and the number of the desired line will be indicated to the operator by means of an indicator. A circuit arrangement of this type is shown in 80 patent to A. E. Lundell and F. A. Stearn, No. 1,345,016, granted June 29, 1920. For the sake of simplicity, it has been assumed that the trunks terminate at the manual office in a jack 14 and that from this point 85 connection may be made by a double plug ended cord. In practice, ringing current will be applied when the assignment key would be depressed in conjunction with a ringing key common to the cords of the position. In the present instance, it has been 90 assumed that ringing current will be applied through the tip and ring conductors of a plug which may be inserted in the jack at the manual office of the trunk.

The first trunk of the group is indicated by conductors 3 and 4. The second trunk of the group is indicated by conductors 6 and 7. The third trunk of the group is represented by conductors 9 and 10. Other trunks 100

of the group, which may be of any desired size, would extend upward on the drawing. Since their interconnection with the remaining trunks of the group would be the same as the interconnection of the first, second and third trunks, it has not been considered necessary to show more trunks.

It will first be assumed that the idle condition of trunks is indicated by the presence of grounded battery on the test terminals of such trunks. When a trunk is seized, the sleeve relay of such trunk is energized and locks up through its left-hand armature. Ground through the test brush of the switch which has seized such trunk will then render this trunk busy to other testing switches. Assuming now that the operator at the manual office at whose position the trunks shown in the drawing terminate, desires to make a group of trunks busy, she will insert plug 12 into the jack of the first idle trunk and apply ringing current to the talking conductors thereof by means of a ringing key (not shown). Assuming that the first trunk is idle, a circuit will then be completed from the source of ringing current 13, ring conductors of plug 12 and jack 14, conductor 4, outer right-hand armature and back contact of sleeve relay 15, winding of relay 16, inner right-hand armature and back contact of sleeve relay 15, conductor 3, tip contacts of jack 14 and plug 12 to ground. Relay 16 is energized in response to the application of ringing current and completes a circuit from grounded battery, right-hand armature and front contact of relay 16, winding of relay 17 to ground. Relay 17 is energized and completes a circuit from grounded battery, winding of slow-release relay 18, outer left-hand armature and back contact of relay 19, inner right-hand armature and front contact of relay 17 to ground. Relay 18 is energized and completes a circuit from a source of busy tone 20, inner left-hand armature and front contact of relay 18, left-hand armature and front contact of relay 17, inner right-hand armature and back contact of relay 15, conductor 3, tip contacts of plug 14 and jack 12 to ground. The tone over this circuit informs the operator that the group of trunks has been made busy, which has been accomplished at the outer left-hand armature and front contact of relay 18, which supplies ground to the test terminals 21, 22 and 23 of the trunks shown through resistances 24, 25 and 26 and sleeve relays 15, 27 and 28 in multiple. When the operator hears the characteristic busy tone, she knows that the group of trunks has been made busy and she thereupon removes plug 12 from jack 14, allowing relay 16 to release. The release of relay 16 causes, in turn, the deenergization of relay 17.

It is to be observed that relay 18 upon energization, prepared a circuit for relay 19, this

circuit extending from grounded battery, winding of relay 18, right-hand armature and front contact of relay 18 and the winding of relay 19 to ground. However, due to the presence of ground on the inner right-hand armature and front contact of relay 17, relay 19 was short-circuited and was not energized at this time. As soon, however, as relay 17 deenergizes the shunt is removed from about the winding of relay 19 and this relay energizes. Relay 19 upon energization completes a circuit from grounded battery, lamp 29, right-hand armature and front contact of relay 19, contacts 30 and 31 of a locking key, through the winding of the magnet of a night-alarm bell indicated at 32 to ground. The ringing of the bell attracts the attention of the wire-chief and upon observing the lighted lamp 29, she depresses the locking key associated with such lamp. The operation of the key opens the circuit for the alarm bell but allows the lamp to burn dimly due to the introduction of a resistance 33 in the circuit of lamp 29. The circuit of lamp 29 now extends through the key contacts 30 and 34 and resistance 33 to ground.

When the operator desires to again make the group of trunks available for use by automatic switches, she again inserts plug 12 into the jack of the first trunk and applies ringing current as before. Relay 16 is again energized and causes in turn the energization of relay 17. Relay 17 upon energization completes a circuit from grounded battery, outer right-hand armature and front contact of relay 17, inner left-hand armature and front contact of relay 19, the winding of relay 19 to ground. Relay 19 is maintained energized in this circuit, but due to the presence of direct battery relay 18 is shunted down and in releasing, removes the busy condition from the test terminals of the trunks. An idle tone is supplied to the operator at the manual office from a source of idle tone potential 35, inner left-hand armature and back contact of relay 18, left-hand armature and front contact of relay 17, inner left-hand armature and back contact of relay 15, conductor 3, tip contacts of jack 14 and plug 12 to the operator's headset. Upon hearing this characteristic tone, she will understand that the group of trunks has been made idle and will remove the plug 12 from jack 14, causing the deenergization of relay 16 and in turn, the deenergization of relay 17. The deenergization of relay 17 causes the release of relay 19. This relay, upon releasing, completes a circuit from grounded battery, lamp 29, right-hand armature and back contact of relay 19, closed contacts 36 and 37 of the key, which is in its locked position, and the winding of the night-alarm bell magnet 32 to ground. The lamp 29 is lighted brightly in this circuit and the alarm bell is caused to ring. The wire-chief thereupon restores the

key to its normal position. The apparatus has now all been restored and the trunks may be used in the regular manner; and the operator may again, at any time, make the group 5 of trunks busy in the same way as just described.

It should be observed that if at the time the operator desires to make the group of trunks busy, the first trunk is in use, she will 10 plug into the second trunk, provided that it is idle. In this case ringing current will be supplied to relay 16 through the right-hand back contacts and armatures of relay 27 and the right-hand front contacts and armatures 15 of relay 15. If the first and second trunks are busy at the time she desires to make the group busy, ringing current will be supplied through the right-hand contacts and armatures of relay 28 and the right-hand front 20 contacts and armatures of relays 27 and 15 since, due to the busy condition of these trunks, their associated sleeve relays will be in an actuated condition.

What is claimed is:

25 1. In an interoffice telephone exchange system, an office, a distant office, groups of trunk lines extending from said first office to said distant office, an operator's position at said distant office at which one of said 30 groups of trunks terminates, apparatus at said first office to simultaneously render all the trunks of the group busy, and means under the control of an operator to operate said apparatus over the talking conductors 35 of one of said trunk lines.

2. In an interoffice telephone exchange system, an office, a distant office, groups of trunk lines extending from said first office to said distant office, an operator's position 40 at said distant office at which one of said groups of trunks terminates, apparatus at said first office to simultaneously render all the trunks of the groups busy, and means under the control of an operator to operate 45 said apparatus over the talking conductors of an idle one of said trunk lines.

3. In an interoffice telephone exchange system, a mechanical office, a manual office, groups of trunk lines extending from said 50 mechanical office to said manual office, an operator's position at said manual office at which one of said groups of trunks terminates, apparatus at said mechanical office to simultaneously render all the trunks of the group busy, and means under the control 55 of said operator to operate said apparatus over the talking conductors of one of said trunk lines.

4. In an interoffice telephone exchange 60 system a mechanical office, a manual office, groups of trunk lines extending from said mechanical office to said manual office, an operator's position at said manual office at which one of said groups of trunks terminates, apparatus at said mechanical office

to simultaneously render all the trunks of the group busy, and means under the control of said operator to operate said apparatus over the talking conductors of an idle one of said trunk lines. 70

5. In an interoffice telephone exchange system, an office, a distant office, a group of trunk lines extending from said first office to said distant office, an operator's position at said distant office at which said 75 trunks terminate, a relay at said first office to control the busy or idle condition of all the trunks of said group of trunks, and means to enable said operator to control said relay over the talking conductors of 80 one of said trunks.

6. In an interoffice telephone exchange system, an office, a distant office, groups of trunk lines extending from said first office to said distant office, an operator's position at said distant office at which one of said groups of trunks terminates, a source of ringing current at said operator's position, apparatus at said first office to render all the trunks of the group busy, and means 85 to operate said apparatus as a result of applying ringing current to the talking conductors of one of said trunk lines.

7. In an interoffice telephone exchange system, an office, a distant office, groups of trunk lines extending from said first office to said distant office, an operator's position at said manual office at which one of said groups of trunks terminates, apparatus at said first office to render all the trunks of the 95 group busy, devices under the control of said operator to operate said apparatus over the talking conductors of one of said trunk lines, means to maintain said busy condition when established, and means to remove said busy condition as a result of the 100 re-operation of said devices.

8. In an interoffice telephone exchange system, an office, a distant office, a group of trunk lines extending from said first office to said distant office, an operator's position at said distant office, a relay combination at said first office to control the busy or idle condition of said group of trunks, and means to control said relay combination 110 over the talking conductors of one of said trunk lines.

9. In a telephone exchange system, an office, a distant office, groups of trunk lines extending from said first office to said distant office, an operator's position at said distant office at which one of said groups of trunks terminates, apparatus at said first office to control the busy or idle condition of said group of trunks, means under the 115 control of said operator to operate said apparatus over the talking conductors of one of said trunk lines, and means for indicating to said operator, the busy or idle condition of said group of trunk lines. 120

10. In a telephone exchange system, an office, a distant office, groups of trunk lines extending from said first office to said distant office, an operator's position at said distant office at which one of said groups of trunks terminates, apparatus at said first office to control the busy or idle condition of said groups of trunks, means under the control of said operator to operate said

apparatus over the talking conductors of one of said trunk lines, and means for supplying a characteristic audible tone to said operator to indicate the busy or idle condition of said trunk lines.

In witness whereof, I hereunto subscribe my name this 29th day of August, A. D. 1919.

DAWSON M. TAGGART.
